FLEXIBLE ARCH SUPPORT

Theodore Werkman, Los Angeles, Calif.

Application May 8, 1937, Serial No. 141,452

2 Claims. (Cl. 36—76)

This invention relates to an arch support adapted to be applied to the edge of the sole of a boot or shoe, and preferably consisting of a stamped metal plate having a flange or flanges engaging 5 the face of the sole adjacent its edge.

An object of the invention is to construct the arch support in such a way as to give the same sufficient flexibility to enable the plate to conform or adapt itself to the shape of the edge of 10 the shoe at the point where it is applied, at the same time preserving sufficient rigidity in the arch support to insure that it will operate effectively as an arch support for the shoe.

The arch support is preferably applied to the 15 inside edge of the sole adjacent the forward face of the heel of the shoe, and one of the objects of the invention is to form the arch support with an upper flange having a form which will facilitate the application of the support to the shoe, but 20 which, at the same time, will give the plate sufficient flexibility to enable it to conform to the shape of the sole edge.

A further object of the invention is to improve 25 the general construction of arch supports of this type, with the idea of enabling the arch support to be applied with great facility to the edge of the sole, at the same time insuring sufficient flexibility to enable the support to adapt itself to the shape 30 of the shoe edge without detracting from the rigidity which the support must have to enable it to perform its function of supporting the arch of the shoe.

Further objects of the invention will appear 35 hereinafter.

The invention consists in the novel parts and combination of parts to be described hereinafter, all of which contribute to produce an efficient flexible arch support.

A preferred embodiment of the invention is described in the following specification, while the broad scope of the invention is pointed out in the appended claims.

In the drawing:

Fig. 1 is a perspective of a shoe illustrating an 45 arch support embodying my invention applied to the same.

Fig. 2 is a plan of the arch support as viewed from its upper side removed from the shoe.

Fig. 3 is a side elevation of the arch support as 50 viewed from the inner side.

Fig. 4 is a section taken about in the plane of the line 4—4 in Fig. 1, and passing through the arch support and the adjacent portion of the shoe to illustrate its relation to the sole of the shoe 55 when in position.

In practicing the invention, I construct the arch support preferably of a plate of metal, from which the arch support is stamped. This plate should have sufficient thickness to give it the necessary rigidity, and is preferably formed with one or 5 more flanges to engage the face of the sole of the shoe adjacent to the edge where the device is applied. The flange or flanges on the device facilitate securing it to the edge of the sole, but are constructed in such a way that the vertical 10 plate or web of the device will have sufficient flexibility to enable it to conform to the shape of the edge to which it is applied.

Referring more particularly to the parts, I indicate 15 the arch support which, in Fig. 1, is illustrated as applied to the edge 2 of the sole 3 of a shoe. The arch support is confined in its extent to the shank of the shoe forward of the heel and on one side only of the shoe. It is preferably made as a stamping from sheet metal, and comprises 20 a single rigid plate having a web 4, which is disposed in a substantially vertical plane against the edge 2 of the sole when the device is in use. This web 4 is flanged, and preferably carries an upper flange 5, which is in a horizontal 25 plane and substantially at right angles to the plane of the web 4. The upper flange 5 preferably has a serrated edge so that projecting teeth 6 with notches 7 between the same, are formed along it. These teeth 6 are preferably disposed 30 in pairs, and gaps in the form of slits 8 are cut in the flange extending from a point adjacent or at the web 4 in an inward direction toward the interior of the shoe. These gaps prevent the flange 5 from giving undesirable stiffness to the 35 support. The points, or teeth 6, facilitate positioning the flange 5 when shoving it inwardly over the edge 2 of the sole. The support is preferably applied in the position illustrated just forward 40 of the forward face of the heel 9 of the shoe.

The web 4 has a concavo-convex form in a vertical plane, so as to enable it to fit approximately, or substantially to the shape of the edge 2 where it is applied.

The support also preferably includes a lower flange 10, which is adapted to fit under the sole 3 as indicated in Fig. 4. This lower flange 10 is preferably formed with gaps 11, or reentrant angles, that extend outwardly from the points 50 12 in the vertical plane of the web 4 of the plate. In the construction illustrated, there are two of these gaps 11, so that the "flange" 10 presents the form of two end lobes 13 and an intermediate lobe 14. These lobes preferably have curved 55

edges 15 so as to give them the form of tongues, and to facilitate their being shoved under the sole.

Suitable means is preferably provided for securing the support in place. For this purpose I prefer to provide perforations 16 in the lobes, through which a small fastener such as a small nail 17 may be driven (see Fig. 4).

It should be understood that in practice, the 10 web 4 of the support would have a shape enabling it to fit approximately to the shoe with which it was intended to be worn. However, as there is a slight variation in shoes, the support has sufficient flexibility to enable it to be applied to the 15 edge of the sole of any shoe having an approximate shape to the shoe with which the support was intended to be worn.

It should be understood that this plate is not only concavo-convex in plan at the web 4, but 20 the entire support is curved in a vertical plane (see Fig. 3). This curvature enables the arch support to conform to the downward inclination of the shank of the shoe as it passes away from the heel 9.

25 It will be evident that although the flanges of the device enable it to be securely held on the edge of the sole by reason of the gaps that are cut in these flanges, they do not detract from the flexibility of the support as a whole. In other 30 words, they do not prevent bending of the web 4 in conforming it to the shape of the edge 2 of the sole.

What I claim is:

1. A flexible arch support to be applied to the

edge of the sole of a boot or shoe, said arch support consisting of a single rigid plate having a web confined in extent to the shank of the shoe, and on one side of the shoe only, conforming approximately to the shape of the edge of the sole at the shank and just forward of the heel of the shoe, said plate having an upper flange for engaging over the upper face of the sole, and having a lower flange to extend under the sole, said flanges having gaps formed therein 10 extending through the same from the said web and enabling the web to flex and adapt itself to the shape of the sole edge.

2. A flexible arch support to be applied to the edge of a sole of a boot or shoe, said arch support 15 consisting of a single rigid plate having a web confined in extent to the shank of the shoe on one side only, conforming substantially with the shape of the edge of the sole at the shank and just forward of the heel of the shoe, said plate 20 having an upper flange for engaging over the upper face of the sole, said upper flange having a serrated edge, and having gaps extending completely through the same, said plate further having a lower flange to extend under the sole, said 25 lower flange consisting of a plurality of lobes with gaps formed therebetween extending from a point adjacent the web, said gaps in said flange and between said lobes enabling the web to flex and adapt itself to the shape of the sole edge, said 30 lobes having perforations therein to permit fasteners to be applied through the same to secure the plate to the sole.

THEODORE WERKMAN.
